UNITED STATES PATENT OFFICE.

ELIE W. LABOMBARDE, OF NASHUA, NEW HAMPSHIRE.

PAPER DRINKING CUP AND METHOD OF MAKING SAME.

Application filed April 14, 1921. Serial No. 461,213.

To all whom it may concern:

Be it known that I, ELIE W. LABOMBARDE, a citizen of the United States, and resident of Nashua, in the county of Hillsborough 5 and State of New Hampshire, have invented certain new and useful Improvements in Paper Drinking Cups and Methods of Making the Same, of which the following is a specification.

10 For some years there has been an increasing demand for, and use of, paper cups which are mostly of two kinds or types, either those which are permanently of tumbler shape, or those which are normally flat and so constructed that they can be opened like a bag for use. Advantages of the latter over the former are that the tumbler-shaped cups are relatively expensive to make and occupy much more space 15 for storage or in dispensers. Some people prefer the tumbler-shaped cups on the ground that they are easier to fill and drink from and are more readily handled when filling and drinking.

20 The present invention relates to the flat type of paper drinking cup and the object of the invention is to provide such cups which can be readily opened for filling and can be easily held and manipulated during 25 use.

To this end the invention consists in the cup and in the method of making the same, substantially as hereinafter described and claimed.

26 Of the accompanying drawings:—

Figure 1 is a plan view of a blank which, when folded and pasted, forms a cup made according to my invention.

Figure 2 is a perspective view of a completed cup ready for use.

Figure 3 is a top view of a cup illustrating the partly open condition which its structure causes it to tend to assume.

Figure 4 is a similar top view illustrating how the grasping of the cup for use causes it to quite fully open.

In the manufacture of my improved cups, paper of sufficiently water-proof character is cut to form blanks of substantially the 50 shape shown in Figure 1. Each blank is then creased on five parallel longitudinal lines indicated at 1, 2, 2, 3, 3, so as to form areas or sections a, a , and b, b , and marginal flaps c, c . These parallel lines are not all 55 equi-distant. The sections b, b are of slightly less width than the sections a, a . The

formation of the lines by creasing partially breaks or dis-arranges the fibers of the paper. It is important that the three lines 1, 2, 2, shall be formed by a creasing operation applied on the same side or surface of the paper—that surface which constitutes the inside of the cup when completed. 60

The next operation is to fold the blank on the lines 2, 2 toward the condition illustrated in Figures 2 and 3, and bring the faces of the flaps c, c together and adhesively connect the said flaps near their outer edges only, leaving those portions of the flaps adjacent to the lines 3, 3, unconnected, as shown 70 in Figure 3. The reason for this will be presently explained.

The bottom portion d of the blank is then folded on transverse line 4 and adhesively secured to close the bottom of the cup. The 75 top portion e of the blank may be left projecting but preferably I fold it in on transverse line 5.

Owing to the crease line 1 being formed as stated by action on that surface of the 80 paper which constitutes the inside of the cup when completed, the said cup has a normal tendency to spring partly open as shown in Figure 3. This opening of the cup is then increased by the action of the fingers of 85 the user who, upon grasping the flaps c, c which present a handle, naturally pinches those flaps. As stated, the sections b, b , are of less width than the sections a, a , and the flaps c, c , are not glued together 90 over their entire width. This leaves a slight space which is indicated at x in Figure 3. The pinching action of the user's fingers tends to close the space x and in so doing the sections b, b are drawn together and the 95 consequent pull of the edges of the cup toward each other forces the sections a, a , outward toward the relative positions shown in Figure 4. In other words, the lateral contraction of the wall from which the edge flaps c, c extend causes the other wall to 100 separate therefrom, said other wall flexing or bending outwardly on its crease line 1.

By reference to Figure 2 it will be seen that the folding and gluing of the bottom portion d results in overlapping the lower ends of the flaps c, c and holding said lower ends interlocked with the bottom of the cup. This facilitates the steadyng of the cup when the flaps c, c are used as a fin or handle, 105 both when the cup is being filled and when it is tilted while drinking from it. More-

over it strengthens and stiffens the cup as a whole.

The completed cup presents a front wall *a, a* and a rear wall *b b*. The rear wall is of less width than the front wall and its flaps *c c* present means for drawing the sections of the rear wall toward each other so as to expand the cup for filling it.

Having now described my invention, I 10 claim:—

1. A vertically elongated waterproof flexible cup normally flat, comprising a blank having opposite parallel edges secured together face to face and presenting an 15 elongated flexible handle normally flat against a side of the cup extending from the upper to the lower portion of the cup to steady said cup in use.

2. A vertically elongated waterproof flexible cup normally flat and having a flexible handle comprising integral parallel marginal portions of the material of the cup secured together face to face and extending from the upper portion of the cup sufficient- 25 ly far down the side thereof to steady the cup in use.

3. A flat paper cup comprising a blank having parallel edges folded on lines parallel with said edges, the marginal portions 30 of the blank being secured together face to face and forming an elongated handle.

4. A flat paper cup comprising a blank having parallel edges folded on lines parallel with said edges, one marginal portion being laid back flat against a side of the cup 35 and the opposite marginal portion being secured thereupon, the two marginal portions combined forming an elongated handle.

5. A flat paper cup having a folded bottom and having an integral handle portion permanently interlocked with said folded bottom.

6. A flat paper cup comprising a folded blank having its marginal portions secured together face to face, the lower ends of said marginal portions being secured to the bottom of the cup.

7. A flat paper cup having a front wall with an inwardly turned upper portion 50 forming a double-thick lip, and a rear wall composed of two sections with outwardly turned flaps secured together face to face, the front wall, including its double-thick upper lip portion being vertically creased. 55

In testimony whereof I have affixed my signature.

ELIE W. LABOMBARDE.
